UNITED STATES PATENT OFFICE.

LOUIS G. JULIHN, OF WASHINGTON, DISTRICT OF COLUMBIA, ASSIGNOR TO ELLIOTT-FISHER COMPANY, A CORPORATION OF DELAWARE.

FORM-LOCATING MEANS.

Application filed April 12, 1926. Serial No. 101,593.

This invention relates to form locating means facilitating the accurate location of forms on a platen.

The object of the invention is to facilitate the rapid manipulation or location of forms by means of a sinuous locating edge extended along the form and coacting with a locator over which the sinuous edge of the form will move freely as the form is shifted to selected locations.

Another object of the invention is to provide forms having marginal locating means coacting with a locator which will arrest or tend to arrest the form in successive locations and which will permit the form to move in a single direction in contact with a guide when seeking the desired position as, for instance, a particular line location.

Another object of the invention is to provide a form having marginal locating means designed to have rolling contact with a locator.

A still further object of the invention is to provide a disappearing locator coacting with the marginal locating edge of a form but yieldable in one direction as the form is moved in another direction to selected locations.

A still further object is to provide a form locator adapted to coact with the marginal locating edge of a form and arranged to be retained in an inactive position when its use is not desired.

In the accompanying drawings:

Figure 1 is a fragmentary view of the platen of an Elliott-Fisher billing machine equipped in accordance with my invention, the form being indicated as riding over the locator.

Figure 2 is a similar view with a form completely located.

Figure 3 is a section on the line 3—3 of Figure 2.

Figure 4 is a view on a somewhat enlarged scale of the locator and the locating edge of the form.

Figure 5 is a sectional elevation of a variation in which the locator proper is in the form of a roller.

Figure 6 is a vertical section of the variation shown in Figure 5.

Figure 7 is a sectional showing of a still further variation in which the locator is in the form of a roller mounted to disappear or recede from the locating edge of the

form and also adapted to be withdrawn from use.

For the purpose of this disclosure, the invention is shown in connection with the flat platen 1 of the Elliott-Fisher bookkeeping machine of commerce. This platen is usually mounted in a frame 2 from a side rail of which extends over the platen, a form or paper clamp 3 against which the form 4 is held by the platen which is depressible from the writing plane to facilitate the insertion, removal or adjustment of the form. It is well understood that the printing mechanism moves longitudinally on rails, one of which is indicated at 5 and the clamp 3 is usually provided with a line space scale 6 which facilitates the location of the form or forms on the platen. In many kinds of bookkeeping and billing a plurality of superposed forms are employed and a change of their relation is frequently necessitated as, for instance, in condensed billing. The scale 6 facilitates this rearrangement of the forms and also permits the forms to be so located that when the machine is brought forward to a predetermined position, its printing point will be presented at the proper point with respect to the matter printed or recorded on the form.

To facilitate the positioning of the forms, it has been proposed to provide each form with marginal locating means coacting with a locator in such a manner that, while the form may be moved in the direction lengthwise of its locating edge, the locator will arrest or tend to arrest the form in predetermined successive positions in any of which the form will be accurately located if its movement is discontinued. It is my purpose to improve or make easier the locating operation and also to render the locating margin of the form less liable to mutilation, by imparting to the edge of the form a sinuous contour made up of reversely curved contours resulting in a series of identical compound curves and also defining alternate projections 7 and depressions 8 of identical dimensions and contour. This configuration is not only of such uniformly sinuous character as to facilitate its movement over the locator 9, but it will be noted that the lugs or projections 7 are formed with wide bases and are wholly without corners so that the tendency of these projections to bend or break is reduced to the minimum. The

locator 9 is secured to the frame 2 by a shank 10 and while having a transverse contour conforming to the shape of the recesses 8 is extended vertically (see Fig. 3) a sufficient distance to accommodate the vertical movement of the platen 1. The location of the form on the platen is accomplished when the platen is in its depressed position. The locating edge of the form is moved against the side rail of the platen frame which constitutes an alignment guide and is then moved backward or forward to the proper line location with the sinuous edge of the form moving freely over the curved face of the locator until the selected location is reached. When this is accomplished, the locator will be fitted snugly within a recess of the form and the locating edge of the latter will be in aligning engagement with the aligning guide 2. While this movement of the form in contact with the locator is comparatively free, its freedom of movement may be increased by utilizing a rotary locator 9^a (see Figs. 5 and 6) in the form of a roller mounted in a bearing 11 secured to a shank 10^a.

Obviously the movement of the form past the locator necessitates relative lateral movement of these elements and while the form is the element so moved when the locator is in fixed position as in the first six views of the drawings, it is contemplated to so mount the locator that it may have a fixed location in use or out of use, or yieldingly located so as to yield laterally as the form is moved along the alignment guide in constant contact therewith. For instance: in Figure 7 the locating roll 9^b is mounted in a swinging bearing 12 pivoted at 13 within a recess 14 in the alignment guide. Between the bearing and the bottom of a recess in the guide is mounted a spring 15 encircling a bolt 16 extended outwardly from the bearing 12 and threaded at its outer end to receive a nut 17 by means of which the locator may be adjusted or drawn back into the recess 14 when the use of the locator is not desired. In Figure 7 the locator 9^b is shown in its active position, and it will be obvious that if this roller is engaged by the sinuous locating edge of a form, it will recede or disappear repeatedly within the recess against the resistance of the spring 16 as the form

is moved along against the alignment guide.

In Figure 7 is also shown a stop screw 18 which may be advanced into contact with the bearing 12 to prevent inward movement of the locator, if it is desired to maintain the latter in fixed location. In this event the movement of the form along the guide 60 will necessarily be accompanied by lateral movement of the form instead of lateral movement of the locator.

As regards the term edge employed, particularly in the appended claims, it is to be understood as applying to the edge wall of the sheet as distinguished from the marginal surface.

What I claim is:

1. In combination, a flat platen, a locator disposed at one edge of the platen and having a convexly curved semi-circular face, and a work sheet movable on the platen past the locator to different line positions by pressure exerted on the sheet and having a locator engaging edge formed of alternately reversed curves of the same arc of a circle providing equi-distantly spaced arcuate indentations for receiving said face of the locator to determine line positions of the sheet and a line of intermediate arcuate cams movable on the locator when pressure is exerted on the sheet in the longitudinal direction of the line of indentations and cams.

2. In combination, a flat platen, a work sheet movable thereover to different line positions by pressure exerted on the sheet in a line spacing direction and having a series of locating cams and intermediate notches along one side edge thereof, a guide for engaging said edge of the sheet to square the sheet on the platen, a locator for engaging said notches to locate the sheet in different line positions and yieldingly mounted to be retracted by said cams when such pressure is exerted on the sheet whereby the sheet may be moved to different line positions with its edge constantly engaging said guide, and means for locking the locator in retracted position whereby a work sheet having a straight edge may be used in conjunction with said guide.

In testimony whereof I have affixed my signature.

LOUIS G. JULIHN.
